METHOD AND MEANS FOR PRINTING
FLOOR COVERINGS

Walter B. Frederick, Oakford, and Thomas J. Kelly, Philadelphia, Pa., assignors to Sloane-Blabon, Trenton, N. J., a corporation of New Jersey

Application August 19, 1941, Serial No. 407,460

13 Claims. (Cl. 101—198)

Our invention relates to methods and means for printing designs in paint on a web of material in the manufacture of floor covering and the like. Our invention is directed particularly to printing methods and means wherein a printing block is employed and the block is shifted during the printing operation to spread or blend the paint or other design forming material applied to the surface of a web of material.

It is usual in printing designs in paint on a web of linoleum or felt base material to employ printing blocks which are raised and lowered intermittently. When in their raised position paint is applied to the lower face of the printing blocks after which the blocks are lowered into contact with the upper surface of the web of material to print designs on the web. The web of material is then advanced while the blocks are raised to receive additional paint for application to another portion of the web.

The printing face of the print blocks usually is provided with design elements which are formed with grooves or are cut at right angles to form pins which receive the paint and apply it to the surface of the web. The paint is therefore applied in ridges or spots which do not blend together thoroughly giving an uneven appearance. Furthermore, in some instances the pins when raised from the paint draw paint with them and when the web is advanced the paint thus raised strings out longitudinally of the web onto adjacent areas producing undesirable lines and imperfections in the design.

The patent to Waldron No. 311,342 describes a printing block with mechanism for moving the printing block transversely of a web of material while in its lowered or printing position to spread the paint laterally and obliterate the lines in which the paint is deposited on the material.

The patent to Wagner No. 2,116,455 describes a somewhat similar method and apparatus in which a mash block is shifted transversely of the web of material to blend the edges of the design elements or the paint of over-printed pattern elements to blend the paint subsequent to the printing operation.

While the devices of the Waldron and Wagner patents perform their intended functions, the movement of the printing block transversely of the web produces only a limited amount of blending or spreading of paint and such blending or spreading is in one direction only. Moreover, these constructions do not result in any spreading of the paint longitudinally of the web so as to conceal or eliminate those imperfections due

to dragging of the paint when the block is raised and the web advanced.

In order to overcome these objections to constructions of the prior art and obtain more effective blending of the paint applied to a web of material we have devised novel methods and means for actuating a printing block or mash block whereby the block is moved longitudinally of the web being printed and preferably is moved both longitudinally and transversely of the web through a closed path. In this way the paint when applied over the paint of a base coat or design element is effectively blended therewith to produce delicate shading and improved marble effects. When the movable blocks print on adjacent areas soft design outlines are obtained and in some instances the paint is given a swirled effect which is particularly attractive. Furthermore, by spreading or displacing the paint longitudinally of the web any dragging of the paint which occurs, when the block is raised and the web is advanced will be deposited in an area over which the paint has been spread by shifting of the block and the resulting lines of paint are obscured so that they are not observable and do not impair the design.

So far as we are aware no one heretofore has moved a printing block or a mash block longitudinally of a web of material being printed to blend differently colored paint used in forming design elements.

While the printing block may be moved as described by any suitable means for attaining the desired result we have devised a new type of block shifting mechanism which is simple in construction and easy to produce and install on existing block printing machines.

One of the objects of our invention is to provide a new method for printing designs in paint on a web of material.

Another object of our invention is to provide novel mechanism for shifting a printing block or a mash block while the printing surface of the block is in engagement with the paint applied to a web of material.

A further object of our invention is to coordinate the operation of the block raising and lowering mechanism and the block shifting mechanism to produce more effective blending and spreading of paint than has been possible heretofore.

A particular object of our invention is to provide a novel method and means whereby paint may be spread longitudinally of a web of material in a block printing machine.

These and other objects and features of our invention will appear from the following description thereof in which reference is made to the figures of the accompanying drawings.

In the drawings:

Fig. 1 is a view in elevation of mechanism located at one end of a printing block actuated in accordance with our invention;

Fig. 2 is a view taken on the line 2—2 of Fig. 1 illustrating a portion of a conventional block printing machine having mechanism embodying our invention applied thereto;

Fig. 3 is an enlarged perspective of certain elements embodied in the mechanism illustrated in Figs. 1 and 2;

Fig. 4 is a sectional view of a portion of the construction shown in Fig. 3 taken on the line 4—4 thereof;

Fig. 5 is a perspective of one element embodied in the construction of Figs. 1 to 4; and

Fig. 6 is a diagram illustrating preferred types of blending motion which may be given to a printing or mash block in accordance with our invention.

In the preferred form of our invention illustrated in the figures of the drawings the invention is applied to a conventional block printing machine having a bed 2, over which a web of material 4 is passed longitudinally of the machine beneath a series of printing blocks 6 (only one of which is shown). Each of the printing blocks is raised and lowered by means of a lifting cam 8 which is engaged by a cam follower 10 carried by a vertically movable slide 12. The cam 8 is so formed and actuated that the printing block is moved to a raised position in which paint is applied to the lower face of the block and thereafter is lowered to a printing position in which the paint carried by the printing surface of the block is applied to the upper face of the web 4 of material being printed.

The printing block 6 is provided at its opposite ends with bearing members 14 (Figs. 3 and 5) each of which has a pair of spaced downwardly extending lugs 16 which are formed with elongated openings 18. A rotatable actuating member 20 is carried by the vertically movable slide 12 and mounted in bearings 22 thereon. However, the member 20 extends through the elongated openings 18 in the lugs 16 of the bearing member 14. The block 6 and the bearing members may therefore move transversely of the web and on the bed 2 and with respect to the slide 12 and the actuating member 20.

This transverse movement of the block is effected by shifting means 21 and 23 located at opposite ends of the block and each of which, as shown, includes an adjustable pin 24 carried by an arm 25 on a yoke 26. The opposite ends of the yoke are secured to the actuating member 20 for movement therewith.

The actuating member is rocked in its bearings 22 on the vertically movable slide 12 through an arc of about 90 degrees. This rocking movement is effected by means of an actuating rod 28 which is vertically movable by an operating cam 30 on the cam shaft 32 which carries the block lifting cam 8. The lower end of the actuating rod 28 is provided with a cam follower 34 while the upper end of the rod is positioned to engage a projection 36 on the yoke 26. The operating rod is guided in its vertical movement by a guide member 38 on the frame of the machine and on an upward movement it serves to raise the projection 36 and rotate the yoke 26 and actuating

member in a counter-clockwise direction, as seen in Fig. 3. Thereafter, when the high point of the operating cam 30 has rotated past the follower 34 on the lower end of the actuating rod, the rod descends by gravity allowing the yoke 26 and actuating member to rotate in a clockwise direction.

This rocking movement of the actuating member 20 and yoke 26 causes the adjustable pin 24 of the shifting means to be moved into and out of engagement with the bearing member 14 on the block 6. The block is thus moved transversely of the machine, to the left as seen in Figs. 2 and 3 when the actuating rod 28 is raised and releases the block for return movement when the rod is lowered. This much of the construction is generally similar to that shown and described in the above identified Wagner patent.

In order to shift the block longitudinally of the web a shifting nut 40 is located between the lugs 16 of each bearing member 14 and is provided with threads which engage threads 42 on the rotatable actuating member 20. Rocking movement of the actuating member therefore causes the shifting nut 40 to be moved back and forth lengthwise of the actuating member and longitudinally of the web of material being printed. The opposite faces of the shifting nut 40 engage the adjacent faces of the lugs 16 on the bearing member, causing the bearing member and block 6 to be moved back and forth lengthwise of the machine as the actuating member is rocked back and forth by the actuating rod 28.

With this construction the rotation of the cam shaft 32 to actuate the lifting cam 8 and raise and lower the printing block 6, also serves to actuate the operating cam 30 in timed relation to the movement of the printing block. The position of the operating cam 30 with respect to the lifting cams 8 is such that the actuating rod 28 is raised to engage the projection 36 on the yoke 26 only when the block 6 is in its lowered or printing position. The yoke 26 then rotates the actuating member 14 to move the printing block longitudinally and transversely of the web of material while the block is in its lowered printing position and while the pins or ribs forming the design elements are in engagement with the paint on the web of material 4.

The printing block and the yoke 26 may be returned to their initial positions by any suitable means. However, in order to cause both ends of the block to be simultaneously moved in the same manner and the yokes 26 positively shifted to their lowered position for engagement by the actuating rod, the block shifting means 21 adjacent the right hand end of the printing block, as shown in Fig. 2, is connected to the shifting means 23 adjacent the left hand end of the block by means of a rod 44 and links 46 connected to the arms 48 on the actuating members 20 at opposite ends of each block. Furthermore, as shown, we prefer to provide duplicate operating mechanism adjacent the opposite ends of each printing block and to locate the operating cams 30 and 30' on the opposite sides of the machine in displaced relation whereby the printing block is positively moved longitudinally and transversely of the web by the mechanism 21 located adjacent one end of the printing block and is positively moved in the reverse directions and back to its initial position by the mechanism 23 located adjacent the opposite ends of the printing block.

With the construction illustrated, upward

movement of the actuating rod 28 adjacent one end of the printing block serves to rotate the yoke 26 and actuating member 14 adjacent that end of the block whereas the links 46 and the rod 44 also serve to cause the block shifting mechanism adjacent the opposite end of the block to be similarly and simultaneously actuated to move both ends of the block longitudinally of the web of material being printed. At the same time or subsequent to the longitudinal movement of the block it is shifted transversely of the web by the adjustable pin 24 of the shifting means 21 at the right hand end of the block. After the actuating rod 28 falls as it passes the high point of cam 30 on the shaft 32, the cam 30' on the opposite side of the machine raises the actuating rod 28 adjacent the opposite end of the printing block and actuates the shifting means 23 adjacent the left hand end of the block. The yoke 26 then rocks the actuating member 20 and the adjustable shifting pin 24 adjacent the left hand end of the block to shift the block back in opposite directions to its initial position preparatory to the next printing operation.

The amount of movement of the printing block (or mash block) actuated in accordance with our invention may be varied considerably and the displacement of the block in either direction, that is, longitudinally or transversely of the web of material may be varied to obtain the desired effect in blending or spreading the paint on the surface of the web. Furthermore, the adjustments may be so controlled that the movement longitudinally of the web may greatly exceed the movement of the block transversely of the web, or conversely the block may be shifted a greater distance transversely than longitudinally of the web.

By adjustment of the shifting pins 24 with respect to the yoke 26 of the shifting means 21 and 23 the manner in which the block is moved may also be controlled. Thus if the shifter pin 24 is adjusted to engage the block 6 at the start of the upward movement of the yokes 26 the lateral shifting of the block and the longitudinal shifting will take place simultaneously and the block will move diagonally through a path somewhat as indicated by the arrow 50 in Fig. 6. On the other hand if the shifter pins 24 are withdrawn so that they do not engage the block until near the end of the rocking movement of the yokes 26 the block will move somewhat as indicated by the arrow 52 in Fig. 6. The adjustments of the pins 24 may also be such that they are retracted so that they do not engage the blocks at all, in which case the blocks will be moved back and forth longitudinally of the web without any transverse movement whatever, as shown by the arrow 54 of Fig. 6.

Similarly, the amount of longitudinal movement may be varied as desired by using alternative actuating members with threads 42 thereon of different pitch or by adjusting the length of the actuating rod 28 to vary the arc through which the yoke 26 and actuating member 20 are rocked on each rotation of the operating cam 30.

These and other changes in the construction and operation of the various elements of the combination may be made without departing from our invention. Similarly, the invention may be used in various ways for actuating printing blocks to print and blend the paint, or for actuating mash blocks to blend paint previously applied to a web of material.

In a preferred method of utilizing our invention the printing blocks are used to simultaneously print and blend paint in overprinting operations. The overprinted paint is then directly carried down through the layer of paint first applied to the web and is distributed both vertically and horizontally so that wear does not detract from the beauty of the design. Moreover, the fresh paint does not have an opportunity to spread or to set before being displaced and blended into the background coat by the print block. The distribution and blending of the paint is therefore controlled more accurately by the print block than is possible by the mash block and very delicate designs and shading of colors are obtained.

We have also found it of advantage in some cases to print a base or primary design on the web and to use a mash block for smoothing the colors of the primary design before overprinting additional design elements. Thereafter paint may be applied in overprint designs to the smooth but still wet paint of the primary design and the printing block by which the overprinted paint is applied may be shifted as it prints to blend the overprinted paint into the background while leaving the intervening areas smooth and uniformly printed. The use of a mash block on the paint of the primary or base design also appears to improve the blending of the overprinted paint by presenting a uniform thickness of paint for receiving the overprint. The shifting of the printing block then produces uniform blending of the overprinted paint and serves to smooth it into the primary design without disturbing those areas which are not overprinted. The "swirled" effect of the overprint, which is desirable in some designs, is generally more pronounced in those instances wherein the background design is first smoothed by a mash block, particularly when the movement of the block is of the angular or arcuate type represented by the arrow 52 in Fig. 5.

While the method described is preferred in many cases our invention is not limited thereto and it should be understood that the constructions shown in the drawings, and herein particularly described are intended to be illustrative of typical embodiments of our invention and are not intended to limit the scope thereof.

We claim:

1. The method of printing designs in paint on a web of backing material by means of a block printing machine, which comprises the steps of applying paint to one block of the machine and printing on said web with said block, thereafter applying differently colored paint to a second block of the machine, printing with paint from said second block on the area printed by the first block while the first paint is still wet, and moving the second printing block in a plane parallel to the web and while engaging the paint thereon whereby the paint from the second block is blended into the paint from the first block as it is applied to the web.

2. A method of printing floor coverings which comprises the steps of printing a background design on a web of material, smoothing out the paint of said background design, thereafter overprinting a design in paint on said smoothed background design while the paint of said background design is still wet, and shifting the overprinted paint longitudinally of the web while leaving the paint in other areas of said web substantially undisturbed.

3. A method of printing floor coverings on a block printing machine which comprises the steps of printing with certain blocks of said machine onto a web of material, moving a mash block into engagement with the paint so printed to smooth said paint, thereafter printing with other blocks of said machine upon the smoothed paint applied by the first blocks while said paint is still wet, and shifting the latter blocks longitudinally of the web while in engagement with said paint.

4. In a block printing machine, a printing block, means for moving a web of material step by step longitudinally of the machine beneath said printing block, means for moving said block into position to apply paint to the surface of said material while said material is at rest, and means for moving said block longitudinally of the machine while in said printing position.

5. In a block printing machine, a printing block, means for moving said block into and out of printing position, means for intermittently moving a web of material longitudinally of the machine between successive printing operations, and means for moving the block longitudinally of the machine during a printing operation.

6. In a block printing machine, a printing block, means for moving said block into and out of printing position, means for intermittently moving a web of material longitudinally of the machine between successive printing operations, and means for moving the block longitudinally and transversely of the machine during a printing operation.

7. In a block printing machine having a printing block, means for raising and lowering said block, means for moving said block in one direction in a plane parallel to the surface of material to be printed, means for moving said block in another direction in said plane and means coordinating the operation of said means to cause said block to move through a closed path in said plane and while in its lowered position.

8. In a block printing machine of the type used in printing designs in paint on linoleum or felt base material for producing floor coverings and the like, a printing block, mechanism for moving said block from a raised position in which paint is applied thereto to a lowered position in which the block will apply paint to the surface of the material to be printed, means for moving said block in two directions in a plane parallel to said surface and elements coordinating the operation of said means and said mechanism to cause said means to be actuated only when said block is in said lowered position.

9. In a block printing machine having a printing block and means for raising and lowering

said block, the combination of means for moving said block in a plane parallel to the surface of the material being printed comprising a threaded member and actuating means operable in timed relation to said block raising and lowering means to rotate said threaded member and shift said block while the block is in its lowered position.

10. In combination with a block of a block printing machine, means for moving said block longitudinally of the machine comprising a vertically movable slide for raising and lowering said block, an actuating member carried by said slide and having threads thereon, means for rocking said member about a horizontal axis and means movable with said block and engaging the threads on said member to shift the block relative to said slide when said member is rocked.

11. The method of printing floor covering and the like by means of a block printing machine which comprises the steps of applying paint to the face of a web of backing material and while said paint is still wet, applying differently colored paint to a printing block, moving said block and the paint carried thereby into position to contact the paint first applied to the web of backing material and shifting said printing block both longitudinally and transversely of the web while in said position to blend the paint carried by said block with that first applied to the web of backing material.

12. The method of printing designs in paint on a web of backing material by means of a block printing machine, which comprises the steps of applying paint to the upper face of the web, applying additional paint to a printing block, moving said block into position to deposit paint in the form of a design over that already applied to the web and while that first applied is still wet, and moving said block while in said position to displace the paint of both layers in directions both longitudinally and transversely of the web to blend the over-printed paint into that first applied and at least partially to mutilate the design in which the paint is applied by said block.

13. The method of printing floor covering and the like by means of a block printing machine, which comprises the steps of applying paint to the face of a web of backing material, applying additional paint to a printing block, moving said block and the paint carried thereby into position to engage the paint on said web and imparting a stirring movement to said block to blend said additional paint with that first applied to said web while said paint is still wet.
